[57] CLAIM

The ornamental design for a ceiling-mounted console, as shown and described.

DESCRIPTION

FIG. 1 is an isometric view of a ceiling-mounted console constructed in accordance with the present invention; FIG. 2 is an enlarged bottom view of the ceiling-mounted console depicted in FIG. 1;

FIG. 3 is an enlarged rear view of the ceiling-mounted console shown in FIG. 1, the front view being a mirror image thereof; and,

FIG. 4 is an enlarged left-side view of the ceiling-mounted console, the right-side view being a mirror image thereof.
